UNITED STATES PATENT OFFICE.

WILLIAM J. LINN, OF PITTSBURGH, PENNSYLVANIA, ASSIGNEE TO LINN MOTOR SERVICES COMPANY, OF PITTSBURGH, PENNSYLVANIA, A CORPORATION OF DELAWARE.

CHOKE CONTROL.

Application filed October 31, 1924. Serial No. 747,940.

The present invention relates broadly to means adapted to assist in maintaining a carbureter choke in such position as to afford enrichment of the mixture supplied to an automotive engine. More particularly, the invention is to provide a device of this character adapted for use on automobiles of the type in which the choke control quite frequently extends through the dash wall to one side of the operator whereby it is not any too readily accessible, or in which no means is provided for holding the control even temporarily in the position to which it may be moved by the operator. At the present time it is possible to purchase on the market different forms of friction grips adapted to be used in conjunction with choke controls. These grips have ordinarily, however, required accurate positioning and the drilling of one or more holes through the dash to permit their attachment. Also, they have been so constructed as to exert an unnecessarily large amount of friction on the control, thereby not only making the initial operation of the choke more difficult, but requiring a positive act on the part of the operator in moving the choke to its normal position.

It is well recognized in the art to which the present invention relates that the full choke effect is necessary only for a comparatively brief period in starting. If the full choke effect is continued there is a tendency for the carbureter to flood. It is also generally desirable to gradually decrease the choke effect as the engine temperature increases.

It is one of the objects of the present invention to provide a choke control that can be easily and quickly applied, and which does not require any preliminary positioning or hole drilling.

A further object of the invention is to provide a control grip of the character referred to of such construction that it will automatically insure a slight movement of the choke control from its fully applied position toward an intermediate position, and one in which continued operation of the motor to which the grip is applied will permit the control to gradually return to its normal position without attention by the operator.

In the accompanying drawings, there are shown, for purposes of illustration only, certain preferred embodiments of the invention, it being understood that the drawings do not define the limits of the invention, as changes in the construction and operation disclosed therein may take place without departing from the spirit of the present invention or the scope of my broader claims.

In the drawings:

Figure 1 is a side elevation of a choke control in position on a car, with my improved control grip in operative position:

Figure 2 is a perspective view of one embodiment of the control grip; and

Figure 3 is a transverse sectional view through a slightly different embodiment of the present invention.

With certain forms of standard installation, the choke control comprises a substantially vertically extending rod 2 leading at its lower end to suitable connections for controlling the air shutter or choke valve and at its upper end connected to one arm of a bell crank lever 3. This lever is pivoted at an intermediate point to a bracket 4 which is normally secured in position by fastening means 5. The other arm 6 of the bell crank lever extends upwardly and has connected thereto a pull rod 7 which passes through the rear motor partition 8 and the dash 9. The forward end of the pull rod is provided with a knob or other suitable means 10 by reason of which the operation of the control is facilitated.

From a practical standpoint it is desirable where attachments are provided to have them so constructed that they may be readily applied, preferably without the drilling of any additional holes. The present control grip embodies these desirable characteristics, the grip preferably comprising a length of wire, rod or other material bent upon itself to provide substantially parallelly extending gripping arms 11 and a fastening eye 12. This eye is of such size as to receive one of the fastening means 5 for the bracket 4, whereby it is possible to install the grip by merely removing one of the bolts or fastening means and passing it through the fastening eye. Preferably, the grip will be provided with a fastening means exactly as shown in Figure 2 of the

drawings, whereby in the event of loss or destruction of one of the fastening means normally provided for the bracket 4 there will be no difficulty in attaching the grip.

- 5 The gripping arms 11 are of such length that they will project upwardly to a point beyond that at which the pull rod 7 passes through the rear motor partition 8. In installing the grip, these arms are spread to 10 an extent to permit the pull rod to pass therebetween, whereby the resiliency of the arms and their tendency to return to their normal position exerts a gripping action on the pull rod. The size of the grip and the 15 character of the material is preferably such that the frictional gripping action thereof will not be great enough to positively hold the choke control in any definite position when the vehicle to which it is attached is 20 running. With such a construction the vibration afforded by operation of the vehicle tends to gradually release the choke control and permit it to return toward its fully off position. This is highly desirable, as the 25 requirement for a choke becomes less as the motor becomes hotter. The present grip, therefore, automatically operates to produce advantageous results.

It is also well recognized in the art that 30 it is unnecessary to utilize the full choke effect for more than a brief instant. With the present construction, the grip acts to throw the choke control from its fully applied position toward an intermediate position. This operation is accomplished by 35 reason of the fact that the lever arm 6 during operation moves in the arc of a circle A. After the arm 6 passes a position during its movement toward the partition 8 in which 40 it is normal to the axis of the pull rod 7, the upper end tends to swing downwardly. This draws the pull rod further toward the fastening eye 12 and separates the gripping arms 11 to a greater extent. This throws 45 an additional strain onto the grip and the resulting tendency is for the arms to return even more quickly toward their original position. The upward thrust exerted by the closing tendency of the arms, due to the 50 angularity of the pull rod 7 and the character of the bell crank lever, is effective for returning the choke control to some extent toward its normal position.

In operation, the driver of the vehicle 55 pulls the choke completely out and holds it until he has stepped on the starting button. Thereafter, merely releasing the pull rod permits it to return toward an intermediate position, whereupon continued operation of 60 the vehicle will be effective for gradually

returning the choke control toward its completely off position.

In Figure 3, there is illustrated a slightly modified form of construction, indicating the possibility of providing the gripping arms 65 11' with serrations or roughened gripping surfaces 13, whereby the amount of grip exerted by the arms may be effectively varied.

The advantages of the present invention 70 arise from the provision of a control grip adapted to be applied without the drilling of additional openings and without any requirements for initial accurate positioning.

Further advantages arise from the construction of the grip, whereby its holding ability varies in accordance with different positions of the choke control, thereby automatically insuring movement of the control 75 toward normal position, as pointed out.

I claim:

1. The combination with a choke control comprising a supporting bracket and a bell crank lever carried thereby with a pull rod connected to one of the lever arms, of a grip 85 provided with fastening means common to said bracket and having parallelly extending gripping arms adapted to embrace the pull rod, substantially as described.

2. As an article of manufacture, a choke 90 grip comprising a body of elongated material bent upon itself to form an eye and substantially parallelly extending arms terminating at a point remote from the eye, said arms having serrated gripping surfaces, substantially as described.

3. The combination with a choke control rod movable longitudinally and also having a slight vertical movement between limits, of a grip therefor comprising a pair of arms 100 yieldably movable away from each other and between which said rod is passed and which are spread apart by the rod, said arms being spread to a greater extent by the rod when it is at one limit of its vertical movement 105 than when it is at the other limit thereof.

4. The combination with a reciprocable choke control rod movable from a full choke to a full open position, of a grip therefor comprising a pair of arms yieldably movable away from each other and between which the rod extends and which are spread apart by the rod, said rod spreading the arms to a greater extent in the full choke 110 position of a rod than in the full open position thereof.

In testimony whereof I have hereunto set my hand.

WILLIAM J. LINN.
